The ornamental design for a display with transitional graphical user interface of a gaming machine as shown and described.

DESCRIPTION

FIG. 1 is the first image in a sequence for a display with transitional graphical user interface of a gaming machine showing our new design;

FIG. 2 is a second image thereof; and,

FIG. 3 is a third image thereof.

The appearance of the graphical user interface sequentially transitions between the images shown in FIGS. 1-3. The process or period in which one image transitions to another forms no part of the claimed design. The broken lines at the perimeter of the figures illustrate the display screen and the remaining broken lines illustrate portions of the transitional graphical user interface. None of the broken lines form part of the claimed design.
